United States Patent

Des. 235,429
Patented June 17, 1975

235,429

DOOR FOR AN AUTOMOBILE

Gordon M. Brown, West Bloomfield, Mich., assignor to
General Motors Corporation, Detroit, Mich.

Filed Aug. 29, 1973, Ser. No. 392,422

Term of patent 3½ years

Int. Cl. D12—08

U.S. Cl. D12—196

FIG. 1 is a side elevational view of a door for an automobile showing my new design;

FIG. 2 is a top plan view taken generally along the plane indicated by line 2—2 of FIG. 1;

FIG. 3 is a sectional view taken generally along the plane indicated by line 3—3 of FIG. 1;

FIG. 4 is a sectional view taken generally along the plane indicated by line 4—4 of FIG. 1; and

FIG. 5 is a sectional view taken generally along the plane indicated by line 5—5 of FIG. 1.

The broken lines in the drawing are for illustrative purposes only.

I claim:

The ornamental design for a door for an automobile, substantially as shown and described.
